FIRE PREVENTION SYSTEM FOR FUEL TANKS

Frank L. Healy, Dongan Hills, and John J. Connors, Brooklyn, N. Y., assignors to Todd Shipyards Corporation, a corporation of New York

Application April 15, 1949, Serial No. 87,662

6 Claims. (Cl. 220—88)

1

This invention relates to gas inertion systems and apparatus. Tanks, reservoirs or chambers used for the reception or storage of inflammable liquids, such as oil or gasoline, when empty or only partially filled, contain atmospheres which are frequently explosive. Under such conditions there is great danger in introducing an open flame into such chambers as may occur if repairs are to be made therein by welding or burning. For example, if the oil storage tanks of an oil tanker require to be repaired, great care must be observed to see that the fumes left in the oil tanks after withdrawal of the oil do not accumulate in the air in such proportion as to explode when the welding torch is used. Many accidents have resulted from such causes.

It has been proposed to avoid danger of explosion by introducing carbon dioxide or other inert gas into the chamber in such quantity as to reduce the oxygen content of the atmosphere to a point where explosion cannot take place. Where the chambers in which the atmosphere is to be inerted are very large, as for example in the case of the storage tanks of a tanker, the quantity of inert gas which must be introduced is very great and the process of inerting, therefore, excessively costly, unless a very cheap source of the inert diluent gas can be provided.

In accordance with the present invention, a system of gas inertion is utilized which comprises introducing into the chamber in which the atmosphere is to be inerted, purified products of combustion, such as flue gases from a boiler or oil burner or exhaust gases from an internal combustion engine. Such gases consist largely of nitrogen and carbon dioxide and if the proper amount of such gases is introduced as to reduce the oxygen concentration in the atmosphere in the chamber sufficiently, then the atmosphere will be non-explosive. As the proportion of nitrogen in the flue gases greatly exceeds the amount of carbon dioxide, the flue gases are much superior for inerting purposes to carbon dioxide alone. For example, if there is water present in the tank or chamber to be inerted, much carbon dioxide may be dissolved and will therefore be ineffective in displacing oxygen from the atmosphere. Furthermore, the carbon dioxide is much heavier than the atmosphere so that it tends to settle to the lower part of the chamber where there may be unnecessary concentration while the upper parts of the chamber still contain higher than the safe proportion of oxygen. This makes it difficult to determine when a safe inertion of the chamber has been reached as a

mere quantitative measurement of the amount of carbon dioxide introduced into the chamber cannot be relied upon. Nitrogen is not subject to these disadvantages of carbon dioxide and therefore makes a more effective inerting medium while at the same time being cheaper.

Difficulty, however, has been experienced in using flue gases or products of combustion for the reason that such gases almost always contain substantial amounts of sulphur dioxide, resulting from combustion of the sulphur content of the oil or other fuel. The presence of sulphur dioxide renders the gases highly corrosive of the metal of which the tanks are constructed. Removal of the sulphur dioxide is therefore required if the gases are to be successfully used. If the sulphur dioxide can be reacted so as to form carbon dioxide, that is also advantageous as increasing the carbon dioxide content of the inerting gases.

In order to assure that the oxygen content of the inerting gases has been reduced to the desired degree, it is desirable to provide carbon dioxide indicator, recorder and control devices suitably associated with the source of the flue gases and apparatus for supplying them to the tanks to be inerted. The amount of carbon dioxide in the flue gases as shown by the carbon dioxide indicator is a reliable measure of the degree of removal of the free oxygen during the combustion process.

Various sources of flue gases may be employed. For example, the flue gases may be withdrawn from the flue of the main power plant of the vessel; alternatively, a separate auxiliary boiler system may be utilized, the flue gases of which are used for inerting the atmosphere while the steam produced is utilized for providing the power to force the gases through the purifying filter and into the tank to be inerted and to operate the necessary auxiliaries. In some instances, instead of providing an auxiliary boiler plant, a special oil burning unit may be provided to produce sufficient flue gases for the purpose.

For purifying the gases, scrubbers or filtering means are provided and preferably also desiccating units for drying the gases before introduction into the chamber into which the atmosphere is to be inerted. For the removal of sulphur dioxide, very satisfactory results are obtained by using a scrubbing tank or tower containing a body of broken limestone. Sprays or jets are provided at the top of the receptacle or tower so as to spray water down over the limestone. As the flue gases pass upwardly through

the fragments of wet, broken stone, the sulphur dioxide in the gases is effectually washed out, most of it combining with the calcium carbonate so as to form additional carbon dioxide passing off with the flue gases and calcium sulphite which dissolves in wash water. After the gases have passed through the scrubber, they are preferably passed through desiccating chambers to remove as much of the moisture from the gases as possible. Such desiccating chambers may be of any suitable construction and any desired desiccant may be employed. For example, they may contain trays of calcium chloride or the like. Means for regenerating the desiccant may also be utilized, for example, heating coils heated by the hot liquid withdrawn from the scrubber. A plurality of desiccating chambers is preferably provided which may be used alternately, the desiccant in one chamber being regenerated while another chamber is being utilized.

The use of scrubbers and desiccating chambers through which the flue gases are passed, provides effective spark arresters, preventing sparks from the boilers or combustion chambers reaching the explosive atmosphere in the chambers being inerted. These gases are also cooled, particularly in the scrubber, so that they are reduced to a safe temperature before reaching the tanks to be inerted.

Flue gases, when drawn from the stack of an efficient oil burning furnace, contain approximately 85% nitrogen, 12% carbon dioxide, 3% oxygen, and a small percentage of sulphur dioxide. In examples which have been tested, the sulphur dioxide content has been about .043%. Since both nitrogen and carbon dioxide are inert gases and 3% oxygen is not sufficient to support combustion, this combination of gases is an effective inerting medium once the corrosive element, sulphur dioxide, has been removed. With the system of the present invention, the sulphur content has been reduced to less than .010%, an amount which is not harmful to the steel of which the tanks are constructed.

In the accompanying drawings, three systems for application of the present invention are illustrated. It will be understood that various modifications and changes may be resorted to as found most convenient and applicable to the particular installations to be made.

In the accompanying drawings:

Figure 1 is a diagrammatic illustration of an oil tanker which is provided with a system for withdrawing flue gases from the main stack and utilizing the same for inerting the atmosphere in the oil storage tanks of the vessel;

Figure 2 is a diagrammatic or schematic representation of a system utilizing gases withdrawn from the main stack of the propulsion power plant of a tanker;

Figure 3 is a similar representation of a system utilizing a special oil burner for producing products of combustion for inerting purposes; and

Figure 4 is a similar view, showing a system employing an auxiliary boiler to provide the inert gases, the boiler being utilized to supply steam for operating the various auxiliaries.

Referring to Figure 1, 10 represents the hull of a tanker, showing the steam boiler and propelling turbine installation, indicated generally by the numeral 12. The flue gases pass out through the stack 14 to the funnel 16. The oil storage tanks are indicated at 17.

Referring particularly to Figure 2, an offtake pipe 18 having a mouthpiece 20 curved so as to

face the direction of flow of the flue gases, is introduced into the stack 14 and a proportion of the gases are withdrawn by a centrifugal blower 22 driven by an electric motor or other prime mover 24. The gases are discharged into the bottom of a scrubbing chamber or tower 26 which contains a body 28 of coarse broken pieces of limestone, marble or the like, through which the gases may readily pass. In the top of the scrubber, a multiplicity of jets or spray heads 30 are provided which are supplied by a pipe or pipes 32 through which water is pumped by a pump 34 driven by a motor 36. The water passes down over the limestone, washes the sulphur dioxide from the flue gases, and a large part of the sulphur is converted to calcium acid sulphite, which is soluble in water and passes off at the bottom of the scrubber through the discharge pipe 38. The reaction is generally as follows:

The CO₂ formed by this reaction passes off with the flue gas and increases the carbon dioxide content thereof.

It will be seen that the scrubbing tower containing the limestone and having the water sprays at the top thereof will act effectively to cool the gases sufficiently and will also act as a spark arrester, preventing any possibility of sparks or flames from the stack passing beyond the scrubber.

It is desirable to dry the inerted gases before introducing them into the tanks in which the atmosphere is to be inerted. For this purpose, a system of desiccating chambers may be provided, such chambers being indicated at 40, the inlets to the chambers being controlled by valves 42. A plurality of chambers are preferably provided so that one can be used while the others are being regenerated or supplied with fresh desiccating material. Any suitable means for drying the gases may be employed. For example, the desiccating chambers may be provided with a plurality of trays 44 for holding any of the well known desiccating materials, such for example as calcium chloride. Means may be provided for regenerating the desiccating material in one or more of the desiccating chambers while another chamber is being used. For example, the inner walls of the chambers may carry pipe coils 46 through which steam or hot water may be passed so as to heat the chamber not in use and drive the moisture off from the desiccant. The water from the scrubber discharge pipe 38, for example, may be passed through the coil 46 as the water from the scrubber has been raised to a substantial temperature by its contact with the hot flue gases. The purified and dried flue gases coming from the desiccating chambers are led through a pipe 48 to the oil storage tanks 17 (Figure 1) which are to be inerted.

In order to ensure that only gas in which the oxygen content has been sufficiently reduced by combustion is supplied, a continuous CO₂ gas analyzer 60 is preferably used, this being connected by a duct 62 arranged to extract a sample of a gas from the offtake pipe 18 or from any other suitable location in the system. The analyzer 60 may be visually observed and the system properly controlled by the operator, but preferably, automatic controls are operated from the analyzer. These controls desirably act upon a motor speed controller 64 to which they are connected by a conductor 66, such controller governing the speed of the blower operating motor

24, and upon the oil burner or other source of the flue gases through conductor 68. In this way, the character of the combustion can be regulated so as to produce the optimum condition for production of CO₂ and corresponding reduction of free oxygen and the speed of the blower may be varied or the blower stopped if the conditions for production of CO₂ are unsatisfactory. Any suitable type of CO₂-analyzer may be used, such, for instance, as the thermal-conductivity type or the automatic Orsat type. A type which has been found successful is the "Hayes" recorder.

In Figure 3, a self-contained system for supplying inert gas is shown in which the gas is provided by combustion of oil consumed by a burner 78 in a combustion chamber 72. The combustion chamber may be provided with suitable cooling and insulating means indicated generally by the jacket 74. Oil is supplied to the oil burner through a pipe 76 controlled by valve 78 actuated from the CO₂ analyzer 60. The gas is forced through the system by a blower 22 operated by motor 24, the controller 64 of which is actuated from the analyzer 60 as in the construction previously described. In all other respects the system may be the same as that shown in Figure 2.

In Figure 4, another self-contained system is provided in which a small boiler 80 is utilized in the firebox 82 of which oil is burned at a burner 84. The supply of oil to this is controlled by a valve 86 actuated from the gas analyzer 60. The flue gases from the boiler pass through a stack 88 to a scrubber 26 which may be similar to that already described, and after passing the scrubber, the gases pass through a desiccating chamber or chambers 40. In the stack 88 an economizer 90 may be located for heating the boiler feed water and also a coil 92, through which water may be forced by the pump 94 to the sprays 30, in the top of the scrubber 26. Steam from the boiler passing through the pipe 96 may be used to operate the pump 94, a fuel pump 100, and a steam turbine 102 for driving the forced draft blower 104 supplying air to the oil burner 84. The speed of the forced draft blower may be controlled by the valve 106 in the pipe leading from the steam pipe 96 to the turbine 102. Steam from the pipe 96 may also be used to operate the boiler feed pump 108 which draws water from the hot well 110 and passes it through the economizer 90 to the boiler. Steam from the pipe is also used to operate the circulating pump 112 of a condenser 116 in which any surplus steam from the boiler may be condensed. Steam or hot condenser water may be used for reactivating the desiccators if desired.

All of the systems described provide purified and desiccated flue gases having the desired low oxygen content which may be used for inerting the atmosphere in tanks or chambers which are to be repaired by the use of flame producing equipment. All of the systems provide an inerting gas which is of adequate purity to avoid objectionable corrosion and which may be produced in very large quantities at very small expense so as to enable tanks of great size, such, for example as the tanks on an oil tanker, to be treated.

While certain preferred embodiments of the invention have been illustrated and described in detail, it is to be understood that changes may be made therein and the invention embodied in other structures. It is not, therefore, the intention to limit the patent to the specific construc-

tions illustrated, but to cover the invention broadly in whatever form its principle may be utilized.

We claim:

1. A system for inerting the atmosphere in empty cargo oil storage tanks of a tanker having a steam propulsion power plant using oil as a fuel, which comprises means for withdrawing a proportion of the flue gases from the main power plant of the vessel, a scrubber for extraction of sulphur dioxide from said gases, a desiccator, and means for forcing said gases through said scrubber and desiccator to the tank in which the atmosphere is to be inerted, and a device responsive to carbon dioxide concentration in the gases forced through the apparatus for controlling the conditions of combustion of fuel in the vessel power plant and the rate of feed of the gases to the tank to be treated.
2. In a gas inertion system, a fuel burner, means for withdrawing products of combustion from the fuel burner and forcing them to the chamber in which the atmosphere is to be inerted, means through which the gases are passed for removing a substantial proportion of any sulphur dioxide present in such products of combustion and converting such sulfur dioxide into carbon dioxide and a soluble sulfur salt, said carbon dioxide being mixed with the products of combustion so as to augment the supply of inerting gas, said sulfur dioxide removing means comprising a scrubbing chamber containing limestone in lump form and water sprays located in the upper portion of said chamber for spraying water upon said limestone, and a desiccator through which the gases are passed after leaving the scrubbing chamber.
3. In a gas inertion system, a fuel burner, a duct for carrying off at least a portion of the products of combustion from the fuel burner, a blower in said duct, a motor for driving said blower, a scrubber into which said blower discharges for scrubbing sulphur dioxide from said products of combustion, means for conducting the gases from the scrubber to the chamber in which the atmosphere is to be inerted, a carbon dioxide responsive control instrument connected with said duct, means for regulating the conditions of combustion of the fuel burner, and means for regulating the speed of the blower, both of said means being responsive to the action of the carbon dioxide control instrument.
4. In a gas inertion system, an oil burner, means for forcing oil thereto, a control valve for controlling the supply of oil to the burner, a forced draft blower for supplying air to the oil burner, a motor for actuating the same, a speed control device for said motor, a duct for leading the products of combustion from said oil burner to the chamber the atmosphere of which is to be inerted, a blower in said duct, a motor for driving said blower, an automatic control instrument responsive to carbon dioxide concentrations in said duct, connections from said automatic control instrument to the means for controlling the oil feed and to both blower motor speed control devices, and a sulphur dioxide scrubber and a desiccator connected with said duct, through which the gases are passed on the way to the chamber to be treated.
5. In a gas inertion system, a fuel burner, the products of combustion of which provide an inerting gas containing sulphur dioxide, and means for purifying the gas before introduction into said chamber the atmosphere of which is to be inerted, said purifying means comprising a scrubber con-

taining limestone, means for spraying water over said limestone, at least a portion of the sulfur dioxide in the inerting gas being thereby converted into carbon dioxide and a soluble sulfur salt, said carbon dioxide augmenting the supply of inerting gas, and a desiccator through which the gases are passed after leaving said scrubber, said desiccator comprising receptacles for holding a desiccating agent and having a regenerating coil therein, and means for forcing the hot wash water from the scrubber through said regenerating coil.

6. A system as claimed in claim 5, in which a plurality of desiccators are arranged so that they may be used in alternation.
